(No Model.)

J. B. SLITER & C. T. BAZZETT.

VEHICLE SPRING.

No. 281,934.

Patented July 24, 1883.

UNITED STATES PATENT OFFICE.

JEFFERSON B. SLITER AND CHARLES T. BAZZETT, OF WAVERLY, NEW YORK,
ASSIGNORS OF ONE-THIRD TO ALONZO V. C. VAIL, OF SAME PLACE.

VEHICLE-SPRING.

SPECIFICATION forming part of Letters Patent No. 281,934, dated July 24, 1883.

Application filed April 17, 1883. (No model.)

To all whom it may concern:

Be it known that we, JEFFERSON B. SLITER and CHARLES T. BAZZETT, citizens of the United States, residing at Waverly, in the county of Tioga and State of New York, have invented certain new and useful Improvements in Wagon Springs and Gearing, of which the following is a specification, reference being had therein to the accompanying drawings.

10 Our invention relates to improvements in vehicles; and it consists in certain novel features in the springs, fifth-wheel, and vibrating braces, springs, and axles, and outside springs, the construction and arrangement of which will be hereinafter more fully set forth in the specification, and pointed out in the accompanying drawings.

15

In the drawings, Figure 1 is a perspective view, showing our invention. Fig. 2 is a side elevation of one of the springs. Fig. 3 is a cross-section through the center of the front axle, spring-box, and fifth-wheel. Fig. 4 is a longitudinal section of the center of one of the outside springs, showing the vibrating brace and socket therefor. Fig. 5 is a cross-section through the line $x-x$ of Fig. 4. Fig. 6 is a plan view of the bottom or under side of the fifth-wheel. Fig. 7 is a side elevation of the fifth-wheel plates.

25

30 Referring more particularly to the drawings, the springs D are three in number, each having three leaves. The lower leaf of the outside springs is secured at the top or upper side of the spring-bar in front and the axle in rear by clip, the leaf being bent at its ends in the shape of a scroll, D', to describe a perfect circle, and secured to cross-bars K by a loop at its ends, the body resting upon and bolted to said cross-bars.

35

40 The central spring, D', is attached at one end to the lower or under side of the rear axle by a similar clip and bolt, the opposite end being secured by a suitable bolt which passes through lugs b, projecting downward from the upper plate, B', of the fifth-wheel, whereby it occupies a plane below that of the sidesprings.

45

Each spring is provided at its center with a wooden bolster or brace, E, secured by clips h, for the purpose of stiffening or strengthening same. Each spring is bent or curved upwardly at its center, and all are secured to a central

supporting-brace, I, bent centrally to accommodate itself to the position of the central spring. Braces L are secured to the rear axle by suitable clips, and extend forward diagonally and pass through the tubular washer or spring n, located within the hollow or tubular portion m of clip h', as shown in Fig. 4. The object of this is to insure a constant vertical or up-and-down motion to the body, and prevent lateral motion or swaying from side to side. This is attained as follows: When a load is placed upon the springs, and they are depressed, the head l of the brace or rod I is drawn within the tube m and compresses the spring or packing N, and when the pressure is released it resumes its normal position, any tendency to lateral or side motion being counteracted by the brace L on the opposite side.

The fifth-wheel is composed of an upper annular plate, B, having downward-projecting lugs b from its inner circumference, to which the central spring, D', is attached, and a second annular plate, B', provided with a central cross-bar having projecting ends a, through which the ends of the clevis C pass.

The lower plate, B', to which the clevis securing the spring-bar f is attached, moves beneath the upper plate, B, its motion being limited by the shoulders b' of the lugs b, thereby affording a free motion of the front axle independent of the spring-connections.

Thus it will be seen from the foregoing that any motion imparted to the body is transmitted equally to all three of the springs, the body being secured to the scrolls D' and to the central brace, I.

The weight of the load bearing upon the cross-bars K, suspended by the scrolls D', has a tendency to throw the strain toward the center of the springs instead of toward the ends, as is the case in vehicles of ordinary construction, thus assuring an even positive vertical motion, and at once equally distributing the strain to every part of the springs.

Having thus described our invention, what we claim, and desire to secure by Letters Patent, is—

1. A vehicle provided with two exterior springs, each composed of two or more leaves, the ends of the central leaves being curved to form a circular scroll, the ends of said scrolls

forming seats for cross-bars, upon which the ends of the body rest, the lower leaves being attached to clips on the upper side of the axle and spring-bar.

5 2. A vehicle provided with two exterior springs having circular end scrolls, forming seats for the body-supporting cross-bars, and a central spring placed below the plane of the exterior springs, the ends being secured to clips 10 on the rear axle and fifth-wheel, its center secured to a central supporting-brace, the ends of which are secured to the side springs, substantially as set forth.

15 3. A vehicle provided with diagonal side braces, one end of each being secured to the axle, the opposite ends passing through and moving in a tubular socket, of clips secured to the exterior springs, substantially as and for the purpose set forth.

20 4. A vehicle provided with side braces, L, the outer ends being secured to the axle, the inner ends passing through a rubber or spring washer located within the tubular socket of a clip secured to the exterior springs.

25 5. A vehicle provided with side braces, L, the exterior ends passing through the tubular socket m and washer n, and provided with a head, l, adapted to compress the washer within the socket when the springs are depressed, as 30 and for the purpose set forth.

6. In a vehicle, a fifth-wheel consisting of an upper and a lower annular plate, the upper plate being stationary, provided with downwardly-projecting lugs b, to which the central spring of the vehicle is attached, the lower 35 plate being movable and having a cross-bar with projecting ends, through which the clevis passes, the movement of said lower plate being limited by contact of the cross-bar with the shoulders b' of the lug b, as described. 40

7. In a vehicle, the combination of the side springs having circular scrolls, forming seats for the cross-bars, central spring, and side braces, L, the inner ends of which are secured to the exterior springs, as described, and a 45 central brace, I.

8. In a vehicle, the combination of the side springs having the end scrolls, as described, the side braces secured to the axle and exterior springs, the central spring and central brace, 50 I, and fifth-wheel attached to the central spring, as described, and for the purpose set forth.

In testimony whereof we affix our signatures in presence of two witnesses.

JEFFERSON B. SLITER.
CHARLES T. BAZZETT.
